CORSET AND WEARING APPAREL OF A
SIMILAR CHARACTERSabine Levy, Stoken Church, England, assignor to
Caprice Limited, London, England, a British
companyApplication September 5, 1946, Serial No. 694,969
In Great Britain May 21, 1946

1 Claim. (Cl. 2—36)

1

This invention relates to corsets and wearing apparel of a similar character that is to garments having a close fitting trunk-encircling portion which is intended to afford support to the body of the wearer and accordingly includes garments such as corsets, corselettes, girdles, belts and panties which are composed of or incorporate elastic yarn which is stretched when the garment is put on and thus provides constant yielding support for the trunk of the wearer.

Garments of this character are well known which are composed of or incorporate textile fabric made up largely of elastic yarn which is so arranged as to allow the garment to be stretched both in depth and in width, such fabric being known as and hereinafter referred to as two-way stretch fabric. Garments composed entirely of this fabric, particularly corsets, girdles and belts, have been made in a permanently tubular form as distinct from garments which are wrapped around the trunk and temporarily attached at the meeting edges of the garment.

The object of the present invention is to provide an improved garment of the kind specified above and accordingly provides such a garment wherein the trunk-encircling portion is comprised wholly or mainly of two-way stretch fabric and is reinforced locally by strips made of one-way stretch fabric. The local reinforcement provided by the invention is, of course, not intended to embrace any longitudinally stretchable strips or encircling bands provided along the top and bottom marginal parts of the trunk-encircling portion, such as at the waistline of corsets or at the lower leg openings of panties. The present invention makes no claim, moreover, to thus locally reinforcing any brassière portion forming part of a garment which is provided with such local reinforcement in the trunk-encircling portion. The invention is particularly, though not exclusively, applicable to a garment in which the trunk-encircling portion is of permanently tubular form.

In preferred constructions the reinforcing strips extend across the middle area of the front panel and/or the rear panel of the trunk-encircling portion, symmetrical to the vertical centre of the panel to which the strips are applied.

In order that the invention may be more readily understood one embodiment of the invention in the form of a corset garment will now be described in more detail with the aid of the accompanying drawing, wherein:

Figure 1 is a front view of the garment when laid out flat, with part of the front panel re-

2

moved in order to show clearly the local reinforcement applied to the rear panel of the trunk-encircling portion, and

Figure 2 is a similar view from the rear, with a part of the rear panel removed in order to show clearly the local reinforcement applied to the front panel.

The corset garment shown in the accompanying drawing consists entirely of a trunk-encircling portion but will serve to illustrate also the application of the invention to other garments, such as a corset provided with an integral brassière portion or a corset provided with leg portions to constitute a combined corset and knicker garment.

The permanently tubular trunk-encircling garment which forms the corset shown in the accompanying drawing comprises a front panel 1 and a rear panel 2 made from a single piece of two-way stretch fabric or from two or more pieces joined together. On the inside of the front panel 1 and centrally thereof is applied by stitching a strip 3 of one-way stretch fabric, that is, a ribbon or tape incorporating longitudinally disposed elastic yarn, the strip 3 extending from the top edge of panel 1 to the bottom edge thereof. A similar longitudinally stretchable strip 4 is provided at the centre of width of the rear panel 2, and other similar strips 5 may be provided at the junctions between opposite side edges of the front and rear panels. A suitable number of suspenders 6 are stitched to the lower edges of the front and rear panels 1, 2.

On the inside of the upper half of the front panel 1, a number of short strips 7 of one-way stretch fabric of tape or ribbon form are applied by stitching, the strips 7 being arranged in pairs to form two symmetrical groups. The strips 7 in each group are shown as parallel one to the other, but may be mutually inclined, and the symmetrical pairs of strips 7 are inclined downwardly toward the centre strip 3 in chevron formation. These local reinforcement strips 7 which are stretchable longitudinally only are arranged according to the size of the garment and the position which the strips 7 will occupy when the garment is being worn, so as to follow the course and direction of the muscle fibres of the external oblique muscle. The strips 7 commence in positions superficial to the usual endpoint of these muscle fibres, where the transition into a non-elastic fibrous membranous sheath for the rectus abdominis muscle takes place. This muscle runs from the symphysis pubis to the xiphisternum and costal margin and is enveloped in a non-

contractile membranous sheath which when over-stretched does not return to its normal length but maintains its elongated, flabby shape and is then unable to counteract ptosis and herniation of the abdominal viscera. The strips 7 are thus disposed symmetrically on each side of the centre of width of the front panel 1 so as to extend, when the garment is being worn, inwards and downwards, making with the centre strip 3 an acute angle which lies between 30° and 60°. The place where the uppermost pair of strips 7 adjoin the centre strip 3 will be situated at a distance varying from 1" to 4" from the upper edge of the front panel 1, whilst the lowermost pair of strips will reach to within 2½" to 4½" of the lower anterior margin of the garment.

On the inside of the lower half of the rear panel 2 a number of strips 8 of one-way stretch fabric of tape or ribbon form are applied by stitching, the strips 8 being arranged to extend out equal distances on opposite sides of the centre strip 4. The strips 8 need not be parallel one to the other or of equal lengths, as shown in the drawing. The purpose of these rear local reinforcement strips 8, which extend substantially horizontal, from the postero-lateral regions is to afford support to the posterior portion at the plane of maximum girth where sagging of the gluteal muscle tissues is most likely to occur. The positioning of the reinforcement strips 8 in this region prevents the garment "riding" up and down and will give fixity to all redundant muscle and fatty tissue in the lower back and thus also improve an unseemly figure. The position of the strips 8 would vary according to the size of the garment, but would normally commence about 2" from the lower edge of the panel 2 and terminate at 4" to 6" from the upper edge thereof.

The width and length of the one-way stretching strips 7 and 8 and the tension of the elastic yarn employed may be varied according to re-

quirements. A garment may be made in accordance with the invention which employs the front reinforcing strips 7 only or the rear reinforcing strips 8 only, or as shown, both front and rear strips 7 and 8.

I claim:

A garment comprising a close-fitting trunk-encircling portion of permanent tubular form made up of front and rear panels and fabricated wholly from two-way stretch fabric and strips made of one-way stretch fabric applied to said trunk-encircling portion to reinforce same locally, said reinforcing strips consisting of a plurality of strips extending in parallel formation across the lower half of the middle area of the rear panel symmetrical to the vertical center of said rear panel and of a plurality of strips extending in two sets in parallel formation and arranged in downward-pointing chevron formation in the upper half of the middle area of the front panel and symmetrical to the vertical center of said front panel.
